UNITED STATES PATENT OFFICE

102,375

DESIGN FOR A FENDER FOR A CYCLE

Herman L. Kraeft, Cleveland Heights, Ohio, assignor to The Murray-Ohio Manufacturing Company, Cleveland, Ohio, a corporation of Ohio

Application September 17, 1936, Serial No. 64,892

Term of patent 7 years

To whom it may concern:

Be it known that I, Herman L. Kraeft, a citizen of the United States, residing at Cleveland Heights, in the county of Cuyahoga and State of Ohio, have invented a new, original, and ornamental Design for a Fender for a Cycle, of which the following is a specification, reference being had to the accompanying drawing, forming a part thereof.

In the drawing, Fig. 1 is a perspective view of a fender for a cycle, showing my new design;

Fig. 2 is a rear elevation of the same; Fig. 3 is a transverse sectional view, taken as indicated at 3—3 on Fig. 1, or at any other point throughout the length of the fender.

The transverse contour of the fender, as shown by Fig. 3, is substantially the same throughout the entire length of the fender.

I claim:

The ornamental design for a fender for a cycle, substantially as shown and described.

HERMAN L. KRAEFT.
